UNITED STATES PATENT OFFICE.

HERBERT H. HEWITT, OF BUFFALO, NEW YORK.

RAILWAY-CAR JOURNAL-BOX.

1,072,726.

Specification of Letters Patent. Patented Sept. 9, 1913.

Application filed May 8, 1912. Serial No. 696,025.

To all whom it may concern:

Be it known that I, HERBERT H. HEWITT, a citizen of the United States, and a resident of Buffalo, county of Erie, and State of New York, have invented certain new and useful Improvements in Railway-Car Journal-Boxes, of which the following is a full, clear, and exact description.

The invention relates to journal boxes for railway cars and seeks to provide an improved construction which obviates the necessity of employing a key or wedge for holding the journal bearing or parts in position in the box.

15 The invention consists in the features of improvement hereinafter set forth, illustrated in the preferred form in the accompanying drawings and more particularly pointed out in the appended claims.

20 In the drawings, Figure 1 is an elevation of a portion of a car truck with the improved journal box applied thereto, the journal box being shown in section on the line 1—1 of Fig. 3. Figs. 2 and 3 are vertical and horizontal sections on the lines 2—2 and 3—3, respectively, of Fig. 1. Fig. 2 is a view similar to Fig. 2, illustrating the manner in which the journal bearing is placed in or removed from position.

25 The improved box is preferably formed of cast steel or iron and comprises top, bottom and side walls 1, 2, 3 and 4, the top and bottom walls 1 and 2 being integral with the inner and outer side walls 3 and 4. The 30 general outline of the improved box is similar to that now in use. The bottom wall 2 is curved or semi-cylindrical in form and is provided at its outer end with an upturned portion 5. A lid 6 of any suitable construction is pivotally connected to a lug 7 at the forward end of the top wall and closes the forward end of the box. The box is provided with an enlarged rectangular inner end portion 8 having a seat or guideway 9 35 for the dust guard 10.

The wheel axle 11 has a wheel 12 fixed thereto and a projecting journal 13 extending within the box. The journal is provided in usual manner with a flange or collar 14 at 40 its outer end and a shoulder 15 at its inner end. The journal bearing 16 is of usual form and is provided with an angular upper surface and a cylindrical lower surface which engages the journal. At its lower side portions, the bearing is provided with laterally 45 projecting edge flanges 17 and stop lugs 18

and at its inner end the bearing has the usual upstanding flange 19.

In the journal box now in use, the bearing is held in position by a wedge or key 60 which is inserted between the bearing and the upper portion of the box. The inner end of the key is arranged to engage with the upstanding flange 19 to prevent the outward movement of the bearing, the key itself being held against outward movement by inwardly projecting lugs at the outer end of the box. In the present construction, the top wall 1 of the journal box is thickened or reinforced and is recessed on its lower face 65 to form an angular seat 20 which directly engages the upper angular surface of the journal bearing and, at its inner end, the thickened top wall is provided with an angular recess 21 for receiving the upstanding 70 flange 19 at the inner end of the bearing. The recess 21 forms a shoulder 22 at the inner end of the bearing seat 20 and which cooperates with the bearing flange 19 to prevent the longitudinal displacement of the 75 bearing in outward direction.

The journal box is provided with integral guides 23 which project inwardly from the side walls 3 and 4 of the box and depend from the top wall 1. These guides coöperate 80 with the edge flanges 17 and the stop lugs 18 of the bearing to hold the latter in position and prevent its longitudinal displacement toward the inner end of the box.

The journal box is mounted to rock or 85 oscillate in a direction transverse to the side frame of the car truck on in the vertical plane of the axis of the box and of the axle 11. The journal box may be mounted for such rocking movement in any suitable manner. The particular construction shown is similar to that set forth in an application for improvements in car trucks, filed by me December 8, 1911, Serial No. 664,643. As 90 shown in said application, the journal box 95 is provided on its inner side with a laterally projecting journal 24 which is mounted in suitable bearings in hubs 25 and 26 formed at the inner portions and at the outer end, respectively, of the car truck 100 side frame 27. As set forth in said prior application, the side frame is journaled upon the cylindrical end portion 28 of the transverse connecting member or transom 105 of the car truck so that the side frame is free to rock in a vertical plane. The bearing portion at the outer end of the journal

24 is preferably quite large, while that at the inner end is somewhat reduced. To reduce the weight, the trunnion is hollow, but is provided with a transverse strengthening rib 29 at its outer end.

The journal box is removably held in position upon the side frame, as set forth in the application above referred to, by a key 30 extending through its outer bearing portion and engaging the inner face of the hub 26 on the side frame. To strengthen the box and its connection with the journal 24, the inner side of the box is preferably somewhat thickened and is provided with an extra heavy portion 31 from which the journal 24 projects. The enlarged portion 8 at the inner end of the box serves as a strengthening rib, but preferably the box is also provided with integral, external strengthening ribs 32 which extend across the top wall of the box and down partway upon the outer side wall 4, as shown in Figs. 1 and 2.

Inasmuch as the box is mounted to rock in a plane extending through the axis of the journal and transverse to the side frame, it can not only be lifted away from the journal 13 in the ordinary manner, but can also be rocked or oscillated, as indicated in Fig. 4, so that there is ample room to insert or remove the journal bearing 16 over the collar or flange 14 at the outer end of the journal and to effect the engagement or disengagement of the upstanding end flange 19 of the journal with the shoulder 22 at the inner end of the bearing seat 20.

It is obvious that changes may be made in the details set forth without departure from the essentials of the invention as defined in the claims.

I claim as my invention:—

1. A railway car journal box having integral top, bottom and side walls, one at least of said side walls having a laterally projecting integral journal for pivotally connecting the journal box to the truck side frames, said side walls having inwardly projecting guides engaging the edge flanges and stop lugs of the journal bearing and said top wall being thickened or reinforced

and having an angular seat on its lower face arranged to directly engage the upper angular surface of the journal bearing, and said top wall having a relatively deeper recess at the inner end of said seat for receiving the upstanding flange at the inner end of the journal bearing, substantially as described.

2. The combination with a truck member, of a journal box mounted thereon to rock in a transverse vertical plane and having inwardly projecting guides for engaging the stop lugs of the journal bearing and a thickened or reinforced top wall provided with an angular seat for the bearing on its lower face and with a recess at the inner end of the seat for receiving the upstanding end flange of the bearing, substantially as described.

3. The combination with a car truck side frame and wheel axle, of a journal box receiving the journal of said axle and mounted on said frame to rock transversely thereof, and a journal bearing having edge flanges and stop lugs and an upstanding flange at its inner end, said journal box having inwardly projecting guides for engaging the edge flanges and stop-lugs of said bearing and having a thickened top wall provided with an angular seat for directly engaging said bearing and a recess at the inner end of said seat for receiving the upstanding end flange thereof, substantially as described.

4. The combination with a car truck side frame, of a journal box pivoted upon said side frame to rock transversely thereof, said journal box having integral top, bottom and side walls, and inwardly projecting bearing guides integral with said side walls, said top wall being thickened and having an angular bearing seat on its lower face and a recess at the inner end of the seat for receiving the upstanding end flange of the bearing substantially as described.

HERBERT H. HEWITT.
